UNITED STATES PATENT OFFICE.

MANFORD F. TUCKER, OF ROCK RIVER, WYOMING.

MOUNTING FOR SAND-REELS.

1,360,157.

Specification of Letters Patent. Patented Nov. 23, 1920.

Application filed November 24, 1919. Serial No. 340,202.

To all whom it may concern:

Be it known that I, MANFORD F. TUCKER, a citizen of the United States, residing at Rock River, in the county of Albany and 5 State of Wyoming, have invented new and useful Improvements in Mountings for Sand-Reels, of which the following is a specification.

The present invention relates in general 10 to well drilling rigs, and more particularly to mounting for a sand reel which embodies novel features of construction whereby the bearings automatically adjust themselves to the different positions of the shaft as the 15 swing lever is manipulated to bring the friction wheel of the sand reel into engagement with the band wheel or the back brake. In a well drilling rig the sand reel is employed for taking in and letting out the sand line 20 to which some implement such as a bailer is attached, and with the conventional mounting of sand reels the bearings do not swing to accommodate themselves to the different positions of the shaft, with the result that 25 the movement of the swing lever to manipulate the sand reel frequently produces an objectionable strain upon the parts. This strain is avoided by the use of the present sand reel mounting.

30 Among the further objects of the invention are to provide a device of this character which can be used in connection with the standard well drilling rigs now in general use, which provides a safe and secure mounting for the sand reel, which can be readily adjusted to bring the sand reel into proper position for effective operation, and which enables the bearings to automatically adjust themselves to the positions of the sand reel 35 shaft as the swing lever is moved to shift the position of the sand reel.

With these and other objects in view the invention consists in certain novel combinations, arrangements and associations of the 45 parts, as will more fully appear as the description proceeds, the novel features thereof being pointed out in the appended claims.

For a full understanding of the invention reference is to be had to the following description and accompanying drawings in 50 which:

Figure 1 is a fragmentary elevation blacksmith shop side of a rig;

Fig. 2 is a fragmentary transverse section 55 of the tail post journal;

Fig. 3 is a sectional end elevation of the

device shown in Fig. 2, and taken on the line x^3-x^3 , Fig. 4;

Fig. 4 is a sectional plan view of the tail post journal, taken on the line x^4-x^4 , Fig. 60 3, and looking in the direction of the appended arrows;

Fig. 5 is a fragmentary side elevation of the swing lever;

Fig. 6 is a fragmentary side elevation of 65 the device shown in Fig. 5, but with same revolved through a 90 degree arc; and

Fig. 7 is an end elevation partly broken away of the tail post journal and the swing lever in position with the sand reel resting 70 in the bearings thereof.

Corresponding and like parts are referred to in the following description and indicated in all of the views of the drawing by the same reference characters.

75

Referring to Fig. 1, which shows the position of the parts when assembled upon a standard well drilling rig, the numeral 1 designates the platform of the rig, and 2 the usual band wheel which receives power from 80 some suitable source by means of a belt 3. This band wheel operates in the usual manner to drive the walking beam 4 and other parts of the rig such as the bull wheel and calf wheel. The sand reel 5 is located at one 85 side of the band wheel 2 and has a friction wheel 6 rigid upon one end thereof, said friction wheel being adapted to be either swung forwardly into engagement with the band wheel 2 so as to be driven thereby or 90 rearwardly into engagement with the back brake 7 to retard the rotation of the reel. The usual sand line 8 is connected to the sand reel and extends over a guide member at the top of the derrick and thence down 95 into the well in the usual manner. This is all of the standard and well known construction and forms no part of the present invention.

The shaft 9 of the sand reel 5 has one end 100 thereof journaled in a bearing A which is mounted upon the tail post 10, while the other end thereof is journaled in a bearing B on the swing lever 11. This swing lever has the lower end thereof pivotally connected at 12 to the platform of the rig, while the upper end thereof is connected by the usual link 13 to a control lever 14. It will thus be obvious that by manipulating this control lever in the usual manner the 105 shaft 9 can be swung to bring the friction wheel 6 of the sand reel into engagement 110

with either the band wheel 2 of the rig or the back brake 7.

The swing lever 11 is provided at the lower end thereof with a cap or head 15 which has a bifurcated formation, the end of the lever being received between the arms of the bifurcation and rigidly secured thereto by suitable fastening means such as the bolts 16. The sides of the bifurcation are shown 10 as reinforced by the longitudinally extending ribs 15^a, and the end of the cap piece which is provided with the pivot 12 may be reduced in thickness, as indicated on the drawing. Arranged within the bifurcation 15 of the cap piece 15 and between the lever and the inner end of the bifurcation are spaced transversely extending bearing plates 17 which are rigidly secured in position by the bolts 18. Journaled between the bearing plates 17 is a split or divided bearing 19 which is provided at its ends with trunnions 20, said trunnions being journaled in the bearing plates 17. The two halves of the split bearing 19 are rigidly secured together 20 by the bolts 21, and the trunnions 20 have the axes thereof in the line of division of the bearing. This bearing 19 receives the swinging end of the shaft 9 of the sand reel and is rotatable to accommodate itself 25 automatically to the different positions of the shaft as the swing lever is manipulated to adjust the position of the sand reel. The bearing plates 17 are adjustable longitudinally within the bifurcation of the cap piece 15 so that the bearing of the sand reel shaft can be raised and lowered as desired.

The tail post journal A includes a base plate 22 which is rigidly fastened by suitable bolts 23 to the top of the tail post 10. 40 An arched standard 24 is superposed upon the base plate 22 and provided with a flanged base 22^a which is bolted at 25 to the base plate. Opposite ends of the flanged base 22^a of the arched standard are provided with hooked lugs 26 which are adapted to be engaged by suitable brace members 27. The upright sides of the arched standard have a substantially parallel relation with each other and are provided in their 45 inner faces with guide grooves 28, said grooves receiving tongues 29 at the sides of a bearing frame. This bearing frame is shown as including a U-shaped member 30 and a top plate 31 which connects the arms 50 of the U-shaped frame and is fastened to the upper ends thereof by the bolts 32. The base of the U-shaped member 30 and the top plate 31 are provided with corresponding openings which receive the trunnions 33 of 55 a split or divided bearing 34. The axis of the trunnion 33 is in the line of the joint of the divided bearing, and the two halves of the bearing are longitudinally fastened together by the bolts 35. This divided bearing receives the other end of the shaft 9 of the

sand reel and is mounted in such a manner that it can swing and automatically accommodate itself to the different positions of the shaft as the reel is swung back and forth, thereby avoiding undue strain or binding 70 upon the parts. The base of the U-shaped member 30 is engaged by the upper ends of adjusting screws 36 which are mounted in a base plate 22 and which are adapted to be locked in an adjusted position by jam nuts 75 37. In a similar manner the top plate 31 is engaged by the lower ends of adjusting screws 38 which are threaded in the top of the arched standard 24, and which are adapted to be locked against rotation by the jam nuts 39. This construction enables the U-shaped member 30 and plate 31 to be adjusted up and down for the purpose of regulating the height of the sand reel shaft and setting it in the proper position. 85

While I have illustrated and described one particular embodiment of my invention, it will be understood that numerous modifications and changes can be made therein without departing in any manner from the 90 spirit of the invention.

What I claim and desire to secure by Letters Patent is:

1. A swing mounting for sand reels and the like, including a bearing provided at its 95 sides with oppositely extending trunnions, said bearing being divided into complementary sections on a line extending through the axis of the trunnions, a slotted main support and opposed members extending transversely across the slotted portion of the main support and formed with pivot openings receiving the trunnions of the bearing.

2. A sand reel mounting including a standard adapted to be rigidly applied to the 105 tail post of a well rig, a bearing collar receiving one end of the sand reel shaft and pivotally mounted upon the said standard, a bearing collar receiving the opposite end of the sand reel shaft, and a swing lever 110 upon which the said bearing collar is pivotally mounted, the pivotal mountings of the bearing collars upon the tail post and swing lever respectively being such that the bearings swing freely upon the said members about axes transverse of the axis of the sand reel shaft to accommodate themselves to the different positions of the shaft when the swing lever is moved.

3. A sand reel mounting including a standard adapted to be rigidly mounted upon the tail post of a well rig, opposed and transversely disposed members having pivot openings therein, a bearing mounted between the opposed members and provided with trunnions received within the pivot openings, said bearing supporting one end of the sand reel, a bearing supporting the opposite end of the sand reel and formed with oppositely extending trunnions, a 130

swing lever adapted to be pivotally mounted upon the well rig, and opposed members receiving the second mentioned bearing between the same and provided with pivot 5 openings receiving the trunnions therein, said opposed members being mounted upon the swing lever, each of the bearings being mounted to swing about an axis transverse to the sand wheel shaft.

10 4. A sand reel mounting including a standard adapted to be rigidly mounted upon the tail post of a well rig and formed with opposed sides, a frame slidably mounted between the opposed sides and adjustable longitudinally of the sides, a bearing collar receiving one end of the sand reel shaft and pivotally mounted within the said frame, a bearing collar receiving the opposite end of the sand reel shaft, and a swing lever carrying the said bearing collar, each of the bearing collars being mounted to swing about an axis transverse to the sand reel shaft.

5 5. A sand reel mounting including a standard adapted to be rigidly secured to the tail post of a well rig, an open frame slidably mounted upon the standard and adjustable up and down thereon, a bearing collar receiving one end of the sand reel shaft and arranged within the open frame, said bearing collar being pivotally mounted between opposite sides of the open frame, a swing lever, and a bearing collar upon the swing lever for receiving the opposite end of the sand reel shaft, each of the bearing collars being mounted to swing about an axis transverse to the axis of the sand reel shaft.

30 6. A sand reel mounting including an arched standard adapted to be rigidly secured to the tail post of a well rig, an open frame slidably mounted within the arched standard and vertically adjustable thereon, the upper and lower sides of the open frame having pivot openings therein, a bearing collar arranged within the open frame and 45 provided with trunnions which are received

within the pivot openings, said bearing collar receiving one end of the sand reel shaft, a swing lever, and a bearing collar on the swing lever for receiving the opposite end of the sand reel shaft, each of the bearing 50 collars being mounted to swing about an axis transverse to the sand reel shaft.

7. A sand reel mounting including a swing lever adapted to be pivotally mounted upon a well rig and having a slotted portion, transverse bearing plates extending across the slotted portion, a bearing collar pivotally mounted between the bearing plates and receiving one end of the sand reel shaft, a bearing collar for the opposite 60 end of the sand reel shaft, and a support for the second mentioned bearing collar adapted to be applied to the tail post of the well rig, each of the bearing collars being mounted to swing about an axis transverse 65 to the sand reel shaft.

8. A sand reel mounting including a swing lever, a bifurcated cap piece applied to the swing lever and providing a slotted opening, transverse bearing plates extending across the slotted opening, a bearing collar received within the slotted opening and provided with trunnions each pivotally engaging the bearing plates, said bearing collar receiving one end of the sand reel shaft, 75 a bearing collar for the opposite end of the sand reel shaft, and a support for the second mentioned bearing adapted to be mounted upon the tail post of a well rig, each of the bearing collars being mounted to swing 80 about an axis transverse to the sand reel shaft.

In testimony whereof, I have signed my name to this specification in the presence of two subscribing witnesses.
